Inventor:

Clarence E. Ogden.

By Arthur H. Ewald,
Attorney.

UNITED STATES PATENT OFFICE.

CLARENCE E. OGDEN, OF CINCINNATI, OHIO.

ELECTRIC CONTROLLER.

Application filed May 31, 1919. Serial No. 301,045.

To all whom it may concern:

Be it known that I, CLARENCE E. OGDEN, a citizen of the United States, and resident of Cincinnati, in the county of Hamilton, 5 State of Ohio, have invented certain new and useful Improvements in Electric Controllers, of which the following is a full, clear, and exact description, reference being had to the accompanying drawings, 10 forming a part of this specification.

The present invention relates to electric controllers.

The principal object of the present invention is to provide in an electric controller, quick movement and positive stop mechanism, whereby the contact segments are caused to move quickly from speed to speed and to assume a definite position at all times. The slow movement of the contact segments 20 from speed to speed results in arcing between the contacts and consequent damage thereto. A similar damage results from leaving the controller segments in imperfect contact with the controller fingers. It 25 is to overcome those difficulties, that the present invention is principally designed.

A further object of the invention is to provide in connection with quick movement and positive stop mechanism means whereby 30 the controller drum may be rotated into any convenient position for the removal and replacement of contact plates, without the derangement of said mechanism.

Other objects of this invention will appear from the following detailed description thereof, taken in connection with the accompanying drawings.

In the drawings:

Figure 1 is a perspective of a controller 40 constructed in accordance with this invention, the casing being broken away to show the quick movement and positive stop mechanism.

Figure 2 is a similar view of a portion 45 of the controller, the parts being in different relation.

The numeral 1 indicates the casing of an electric controller in which a contact drum shaft 2 is rotatably mounted in the usual manner. Mounted on the shaft 2 are contact segments 3 having replaceable contact plates 4 secured thereto by means of screws 5 or other suitable means. The contact plates 4 are arranged to make contact with fingers 6 in accordance with the usual con-

struction. Rigidly mounted on the shaft 2 is a plate 7, a segment of the periphery of which is provided with alternating points 8 and recesses 9. The outer face of the plate is provided with abutments or shoulders 10. 60

Rotatably mounted on the shaft 2 is a bronze sleeve or bushing 11 on the inner end of which is secured or integrally formed, as may be desired, a finger 12, which is arranged to operate between and contact with either of the shoulders 10 on the plate 7. The outer end of the bushing 11 is square as shown, and serves as a mounting for the controller handle 13. The end plate 14 of the casing 1 is provided on its inner face 70 with a socket 15, arranged to receive a steel ball 16. A compression spring 17 forces the ball 16 against the periphery of the plate 7.

In order to adapt the plate 7 to a controller having replaceable contact plates, the periphery of the said plate, opposite the segment having the points 8 and recesses 9, is provided with a surface 18 arranged to retain the ball 16 in the socket when the 80 drum is rotated to extreme position, as illustrated in Figure 2, for the removal of contact plates normally located on the bottom of the drum.

The operation of the device is as follows: 85

The movement of the handle 13 in either direction does not actuate the controller drum until the finger 12 engages one of the shoulders 10 on the face of the plate 7; movement of the handle thereafter actuates 90 the drum, but does not cause any change in contact until the point 8 on the periphery of the plate which compresses the ball 16 against the spring 17 is eccentrically positioned with respect thereto, whereupon the ball snaps into the succeeding depression, causing the drum to move instantaneously to make the next contacts, the space between the shoulders 10 on the plate 7 permitting 95 such movement without corresponding movement of the handle 13. Each succeeding series of contacts in either direction is similarly effected, and as will be understood, this instantaneous making and breaking of the contacts minimizes the drawing of arcs 100 between the contacts and thus reduces the consequent wear and injury thereto.

As will be seen, furthermore, by reason of the surface 18 on the plate 7, all of the contact plates of the drum may be replaced 110

without the derangement of any of the parts of the quick movement and positive stop mechanism.

A further object achieved by the present invention is the elimination of notches or similar devices from the casing for indicating the correct positions of the controller handle, the positive stop in definite positions being achieved by the plate and spring 10 pressed ball mechanism above described.

Having thus fully described my invention what I claim as new and desire to secure by Letters Patent, is:

1. In an electric controller in combination with a rotatable member, a plate mounted with, and arranged to actuate said member, alternating points and depressions on the periphery of said plate, a member mounted adjacent said plate, means for pressing said member against the periphery of said plate, whereby said member is caused to actuate said plate when either of the points on the periphery thereof is eccentrically positioned with reference thereto, 15 whereby said rotatable member is instantaneously rotated to and secured in definite positions, shoulders on the face of said plate, an operating member loosely mounted in connection with said rotatable member, a finger operable by said operating member between said shoulders and arranged to rotate said plate eccentrically to position the respective points with respect to said compressed member, the space between said shoulders being sufficient to permit movement of said plate by said member independently of said handle.

2. In an electric controller in combination with a rotatable member, a plate mounted with, and arranged to actuate said member, alternating points and depressions on the periphery of said plate, a ball mounted adjacent said plate, means for pressing said ball against the periphery of said plate, whereby said ball is caused to actuate said plate when either of the points on the periphery thereof is eccentrically positioned with reference thereto, whereby said rotatable member is instantaneously rotated to 20 and secured in definite positions, shoulders on the face of said plate, an operating member loosely mounted in connection with said rotatable member, a finger operable by said operating member between said shoulders and arranged to rotate said plate eccentrically to position the respective points with respect to said ball, the space between said shoulders being sufficient to permit movement of said plate by said ball independently of said handle.

with respect to said ball, the space between said shoulders being sufficient to permit movement of said plate by said ball independently of said operating member.

3. In an electric controller, in combination with the casing, a shaft rotatably mounted in said casing, a contact drum mounted on said shaft and contact fingers mounted in the casing, a plate rigidly mounted on said shaft, alternating points and depressions on the periphery of said plate, a member mounted adjacent said plate, means for pressing said member against the periphery of said plate, whereby said member is caused to actuate said plate when either of the points on the periphery thereof is eccentrically positioned with reference thereto, whereby said drum is instantaneously rotated to and secured in definite positions to make desired contacts, shoulders on the face of said plate, a handle loosely mounted on said shaft, a finger operable by said handle between said shoulders, and arranged to rotate said plate eccentrically to position the respective points with respect to said compressed member, the space between said shoulders being sufficient to permit movement of said plate by said member independently of said handle.

4. In an electric controller, in combination with the casing, a shaft rotatably mounted in said casing, a contact drum mounted on said shaft and contact fingers mounted in the casing, a plate rigidly mounted on said shaft, alternating points and depressions on the periphery of said plate, a ball mounted in said casing, means for pressing said ball against the periphery of said plate, whereby said ball is caused to actuate said plate when either of the points on the periphery thereof is eccentrically positioned with reference thereto, whereby said drum is instantaneously rotated to and secured in definite positions to 90 make desired contacts, shoulders on the face of said plate, a handle loosely mounted on said shaft, a finger operable by said handle between said shoulders, and arranged to rotate said plate eccentrically to position the respective points with respect to said ball, the space between said shoulders being sufficient to permit movement of said plate by said ball independently of said handle.

CLARENCE E. OGDEN.
